UNITED STATES PATENT OFFICE.

NORMAN EMILE McCLELLAND, OF LONDON, ENGLAND.

APPARATUS FOR REMOVAL OF SOOT FROM THE SMOKE BOXES AND FIRE TUBES OF MARINE AND LIKE BOILERS.

Application filed July 5, 1923, Serial No. 649,655, and in Great Britain November 16, 1922.

This invention relates to the removal of soot from the smoke boxes and fire tubes of direct tube and return tube types of boilers by means of fixed steam or compressed air 5 blowers.

In boilers of this type soot collects more particularly in the bottom or lower portion of the smoke box and seriously affects the steaming of the boiler, and the effective removal of this soot is dependent upon its disturbance by blower jets designed to keep the soot in suspension and the induction of an up-draught to carry it off.

According to the present invention therefore two sets of steam or compressed air nozzles are provided in pipes fixed horizontally in the smoke box, one set near the bottom of the smoke box being adapted to disturb the deposited soot and keep it in suspension while the other set, at a higher level or levels, is adapted to induce an up-draught to carry off the soot in suspension. In boilers having furnaces at different levels the draught-inducing and the soot-disturbing 20 tubes are arranged at appropriate levels in the various sections of the smoke box. The lower level tubes may, if desired, be provided with upwardly directed draught-inducing nozzles in addition to the nozzles provided 25 for preventing the deposit of soot or disturbing soot already deposited.

The apparatus may be arranged to be swung outwardly so as to leave the boiler tubes easily accessible for replacement or other purpose, and in the case of a smoke box divided into separate compartments the nozzle apparatus of each unit may be separately movable in this manner.

One embodiment of the invention, as applied to a four furnace marine type boiler, is illustrated in the accompanying drawings, wherein Figure 1 is an interior view of the smoke box with the rear wall removed showing the end of the boilers in elevation; Figure 45 1^a is a view showing the interior of the smoke box with the rear wall removed and the end of the boilers in elevation and disclosing a modified form of the invention; Fig. 2 a section on line 2—2 of Fig. 1; Fig. 3 a vertical section on line 3—3 of Fig. 1; and Fig. 50 4 a vertical section on line 4—4 of Fig. 1.

As therein shown a single steam pipe A provided with upwardly directed nozzles A' to the flue A² traverses horizontally the 55 centre sections B, B and wing sections C, C

of the smoke box. The steam supply pipe D which is provided with a control valve D' external to the smoke box is connected with pipe A by a swivel coupling E located at one end of pipe A, the other end of which 60 has a suitable bearing or pivot within the smoke box, so that the pipe can be rotated as a whole about its axis alternatively intermediate swivel couplings E' may be provided to permit the independent rotation of 65 each section or groups of sections as shown in Figure 1^a.

From the centre of each section of pipe A a branch pipe F extends downwardly towards the bottom of the respective sections of the 70 smoke box to convey steam from pipe A to the nozzle pipes G and H in the centre and wing sections respectively. As shown, there are two such pipes in each centre section, the upper pipes being provided with up-draught 75 inducing nozzles G' as well as with nozzle G² adapted to disturb deposited soot. As the soot tends to accumulate mainly in the angle between the tube plate I and the bottom of the smoke box, the steam pipes carrying the 80 soot-disturbing nozzles are located in that angle and the nozzles G² are directed inwardly towards the fire tubes J, and may be spaced as shown to register with the two bottom rows of fire tubes. At each end of 85 the lower pipes G there is a rearward extension provided with nozzles G³ directed towards the back of the smoke box to prevent deposition of suspended soot in that region.

The arrangement of the soot-disturbing 90 nozzle pipes H in the wing sections of the smoke box is similar to that of the centre sections, an additional short length of pipe being provided owing to the irregular level of the smoke box floor in these sections. The 95 uppermost of the pipes H are provided with up-draught inducing nozzles H' in addition to the inwardly directed soot-disturbing nozzles H² and the lower pipes H are provided with rearward extensions at the two ends of 100 the smoke box section having nozzles H³ adapted to prevent deposition of soot at the back of the section.

The several sections of the steam blower are provided with clamps K by means of 105 which they are secured to the smoke box in the operative position. By opening the smoke box doors and undoing clamps K the blower may be swung outwards as a whole or in sections (according to the subdivision 110

of pipe A by intermediate swivel joints E'), leaving the fire tubes accessible for tightening up or other purpose.

Having thus described the nature of the said invention and the best means I know of carrying the same into practical effect, I claim:

1. In a boiler having horizontal fire tubes leading to a vertical flue, an apparatus for the removal of soot from the smoke box of said flue and from the fire tubes comprising a horizontal pipe situated in the upper portion of said smoke box and connected to a supply of gaseous fluid under pressure and 10 nozzles directed upwardly from said pipe and horizontal pipes situated in the lower portion of said smoke box and connected to said upper pipe and nozzles from said lower pipes directed towards the fire tubes and towards 15 the rear wall of said smoke box.

2. In a boiler having horizontal fire tubes leading to a vertical flue, an apparatus for the removal of soot from the smoke box of said flue and from the fire tubes comprising a horizontal pipe situated in the upper portion of said smoke box and connected to a supply of gaseous fluid under pressure and 20 nozzles directed upwardly from said pipe and horizontal pipes situated in the lower portion of said smoke box and a pipe connecting the upper pipe to the lower pipes, and nozzles from said lower pipes directed some 25 vertically upwards, some laterally towards the fire tubes and some laterally towards the rear of the smoke box.

3. In a boiler having horizontal fire tubes leading to a vertical flue, an apparatus for the removal of soot from the smoke box of said flue and from the fire tubes comprising a horizontal pipe fixed in a definite position 30 in the upper portion of said smoke box and connected to a supply of gaseous fluids under pressure and nozzles directed upwardly from said pipe and a double row of horizontal pipes 35 fixed in a definite position in the lower portion of said smoke box, a pipe connecting said upper horizontal pipe to said lower horizontal pipes, and nozzles from said lower pipes directed 40 towards the fire tubes and towards the rear wall of said smoke box.

4. In a boiler having horizontal fire tubes leading to a vertical flue, an apparatus for the removal of soot from the smoke box of said flue and from the fire tubes comprising a horizontal pipe fixed in a definite position 45 in the upper portion of said smoke box and divided into independent rotatable sections each provided with nozzles and horizontal pipes situated in the lower portion of said smoke box and connected to said upper pipe, and nozzles from said lower pipes directed 50 towards the fire tubes and towards the rear wall of said smoke box.

5. In a boiler having horizontal fire tubes

leading to a vertical flue, an apparatus for 65 the removal of soot from the smoke box of said flue and from the fire tubes comprising a horizontal pipe situated in the upper portion of said smoke box and connected to a supply of gaseous fluid under pressure and 70 nozzles directed upwardly from said pipe, and a set of horizontal pipes one row above the other situated in the lower portion of said smoke box and a pipe connecting the lower pipes to the upper pipes and conveying 75 fluid under pressure from the upper pipe to the lower set of pipes and nozzles from said lower pipes directed towards the fire tubes and towards the rear wall of said smoke box.

6. In a boiler having horizontal fire tubes 80 leading to a vertical flue, an apparatus for the removal of soot from the smoke box of said flue and from the fire tubes comprising a horizontal pipe situated in the upper portion of said smoke box and connected to a supply of gaseous fluid under pressure and 85 nozzles directed upwardly from said pipe, and a set of horizontal pipes situated in the lower portion of said smoke box and connected to the upper pipe, one row of said lower 90 horizontal pipes having rearward horizontal extensions with nozzles directed respectively towards the rear of and diagonally across the smoke box.

7. In a boiler having horizontal fire tubes 95 leading to a vertical flue, an apparatus for the removal of soot from the smoke box of said flue and from the fire tubes comprising a horizontal pipe situated in the upper portion of said smoke box and connected to a supply of gaseous fluid under pressure and 100 nozzles directed upwardly from said pipe, and a set of horizontal pipes formed of lengths and adapted to fit the contour of the floor of the smoke box, two of said pipes having rearward horizontal extensions with 105 nozzles extending therefrom directed respectively towards the rear of and diagonally across the smoke box.

8. In a boiler having horizontal fire tubes 110 leading to a vertical flue, an apparatus for the removal of soot from the smoke box of said flue and from the fire tubes comprising a horizontal pipe pivoted in the upper portion of said smoke box and connected to a supply 115 of gaseous fluid under pressure and nozzles directed upwardly from said pipe and horizontal pipes situated in the lower portion of said smoke box, a pipe connected to the upper pipe and to the lower pipes and adapted to be swung outwardly as a whole about the axis of said upper horizontal pipe, and nozzles from said lower pipes directed 120 towards the fire tubes and towards the rear wall of said smoke box.

In testimony whereof I have signed my name to this specification.

NORMAN EMILE McCLELLAND.
